CLAIM

We claim the ornamental design for a spout for packaging container, as shown and described.

DESCRIPTION

FIG. 1 is a perspective view of a spout for packaging container, showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a reference perspective view thereof showing a configuration of use; and,

FIG. 9 is another reference perspective view thereof showing another configuration of use.

The evenly broken lines are shown for the purpose of illustrating both parts of the article as well as environmental subject matter of exemplary containers. None of the evenly broken lines form part of the claimed design.
